UNITED STATES PATENT OFFICE.

NELS M. NELSON AND HENRY F. NELSON, OF WHITE BIRD, IDAHO.

PORTABLE SAWING MACHINE.

Application filed July 3, 1925. Serial No. 41,315.

Our present invention relates to improvements in portable sawing machines of the power operated type adapted especially for use in cutting or sawing up felled timber 5 into log lengths or for cordoning purposes.

Our invention contemplates the use of an automotive machine capable of propulsion from place to place for the performance of sawing operations in the woods, and comprises certain novel features of construction and combinations and arrangements of parts whereby the machine may be adjusted to a log for sawing and relatively fixed in operative position, and from which position the machine may with equal facility be withdrawn for readjustment in completing the cutting up of felled timber into logs. Means are provided for quickly and conveniently converting the power mechanism 20 from use for propelling the machine to the performance of the sawing operations, and other features of merit reside in the machine as will hereinafter be more specifically pointed out and claimed.

In the accompanying drawings we have illustrated one example of the physical embodiment of our invention in connection with a reciprocating saw of the drag type and utilizing a crank movement for the saw 25 blade. The parts are herein combined and arranged according to the best mode we have so far devised for the practical application of the principles of our invention.

Figure 1 is a view in side elevation showing the sawing machine in operative position with a reciprocating, crank operated saw shown in dotted lines.

Figure 2 is an enlarged top plan view showing a portion of the power transmission 40 mechanism, and illustrating also two of the supporting wheels for the machine.

Figure 3 is an enlarged view in side elevation showing the steering wheel and means for anchoring one end of the machine 45 in position during a sawing operation.

Figure 4 is a top plan view of the device shown in Figure 3.

In carrying out our invention we preferably use a light but strong main frame 50 including a pair of converging or angularly disposed bars 1 and 2 that form a V-shape frame from which the transversely disposed axle 3 is supported by hangers 4 beneath the bars, and the axle is journalled in bearings as 5 in these hangers.

At the rear or pointed end of the frame

a castor wheel 6 is located, which supports the frame when the machine is sawing and is used to steer the machine when it is being propelled by power supplied from the motor 60

7. The motor is of suitable type, preferably a gasoline engine and is supported above the frame in position to counterbalance the load of the machine. The transversely arranged drive shaft 8 of the motor is provided with a balance wheel 9 and the operating shaft 10 of the machine is arranged parallel with the drive shaft at the rear thereof and journaled in bearings 11 on the top of the bars of the frame. Power is 70 transmitted from the drive shaft 8 to the operating shaft 10 through the driving sprocket wheel 12 on shaft 8; chain 13 and the driven sprocket wheel 14 on the operating shaft 10. 75

The operating shaft is provided with a crank arm 15 secured on one of its ends for actuating the reciprocating drag saw 16 through the connecting pitman 17, the saw and pitman being shown in dotted lines in 80 Figure 1.

In Figure 1 it will be seen by dotted lines that the front ends of the frame bars are each equipped with a dog as 18 having an arm 19 pivoted to the inner face of the bar at 20. In operating position the frame is pushed forward to bring the front ends of the frame bars to rest on top of the log 21, and then the dogs or spikes 18 are driven into the log for the purpose of attaching 90 the machine frame to the log with the rear end of the frame supported on the castor wheel 6. The reciprocating drag saw is suspended at one side of the machine frame and of course reciprocates transversely of 95 the log and is free to adjust itself to the log as the kerf is cut therein.

The machine frame is adjustable for the purpose of raising or lowering the position of the operating shaft for the purpose of 100 adapting the saw to various diameters of logs to be cut. For this adjustment we provide the castor wheel with a shank or bar 22 having rack teeth 22' and the shank or rack bar is supported in a bushing 23 bolted at the pointed end of the V-shaped frame. The frame is movable vertically and guided by the bushing on the rack bar which latter is of sufficient length to permit of adequate movement of the frame with relation to the 105 rack bar.

A rack wheel 24 is used in co-action with

the teeth 22' of the shank or bar 22 for elevating or lowering the frame with relation to the bar and for directly supporting the frame on the bar when the machine is being transported. This wheel is carried on a transversely disposed shaft 25 having a handle 26, and a U-shaped frame 27 having a pair of spaced bearings or bearing plates 28 is provided to retain the shaft in position. 10 These bearing plates are provided with longitudinally extending, vertical slots 28' to accommodate the shaft and the slots are of such a length as to permit lateral adjustment of the shaft in them. Each bearing plate 15 has a pin as 29 which is passed through vertical openings in the plates to co-act with the plates in retaining the shaft in its bearings.

For anchoring the rear end of the frame 20 in rigid and stable position we employ a metal stake 30 located preferably between the two bars of the main frame and slideable in vertically spaced bushings or guide sleeves 31. A key 30^a engaging complementary grooves in the stake and walls of the bushings prevents rotary movement or turning of the stake upon its axis. At its side adjacent to the rack bar 22 the stake is provided with a set of teeth 32 complementary to those 25 of the rack bar and adapted to be engaged by the rack wheel 24. The rack wheel is adapted for selective use with either of the toothed members—the bar 22 or the stake. The stake, as indicated in Figure 3 is adapted 30 to be driven into the ground with blows from a hammer or maul, to anchor the machine frame against lateral movement. When the machine is to be readjusted or withdrawn from use, the stake is lifted by means of the 35 rack wheel. For this purpose the rack wheel is shifted from its rack bar 22 by first removing the pins or bolts 29, then sliding the shaft with its wheel along the 40 slots of the bearing plates, to the right in Figure 3, to the right ends of the bearing 45 slots. Then the pins are inserted in the perforated bearing plates to retain the shaft in position. By turning the handle 26 the stake will be lifted from the ground, after 50 which the rack wheel and its shaft may be shifted again if desired.

Power from the motor is selectively used 55 for propelling the machine or for operating the reciprocating saw, and a clutch 33 of usual type is provided on the shaft 3 and operated by the clutch lever 34 in usual manner for controlling the transmission of power.

For propelling the machine a driving 60 sprocket 35 is carried on the operating shaft and the chain 36 from this sprocket passes over a driven sprocket wheel 37 on the axle 3. Two supporting wheels 38 and 39, the former 65 a traction or drive wheel fixed on the axle, are provided at the ends of the axle 3, and

it will be apparent that the machine is supported on these two wheels together with the steering or castor wheel 6. As the machine is propelled by power, it is steered or guided manually by use of the steering handle 40 attached at the rear of the main frame.

As thus arranged it will be obvious that the machine may be transported from place to place for sawing operations and readily 75 steered or guided under manual control. In adjusting the machine to the timber after each cut of the saw, the machine may be manipulated with facility to different positions throughout the length of the timber 80 and may with equal facility be alternately fixed in operative position and released from the log and ground with a considerable saving of time and labor. The several parts of the machine are arranged to uniformly distribute the load on the frame, and the minimum number of parts employed insure reliability and facility in operating the machine.

In applying the machine frame to the 90 timber, in order that a wide area of support may be afforded to stabilize the machine, the front ends of the frame bars rest on the timber, the two wheels 38 and 39 rest on the ground, and the third wheel 6 95 also rests upon the ground as an additional support. In order to adapt the machine to receive support at these four points it may be necessary to adjust the rear end of the frame with relation to the castor wheel by 100 manipulating the crank handle 26 of the rack wheel to either lower the frame or raise it with relation to the castor wheel. This adjustment can readily be effected and the load of the machine thus distributed at the 105 four points to insure stability of the stationary parts.

By use of our construction herein specified we are enabled to provide an attachment to the standard sawing rigs so that the devices 110 of our invention may be adapted to any such rig no matter where found by the simple expedient of attaching tractor elements to the usual saw frames by means of the pins or bolts 41, and can as easily be removed 115 by withdrawing the said pins or bolts.

Having thus fully described our invention what we claim as new and desire to secure by Letters Patent is—

1. The combination in a portable sawing 120 machine with a main frame and a removable anchoring stake having rack teeth thereon, of a supporting wheel having a stationary 125 guide member for co-action with the frame, said member comprising a toothed bar loosely supported in a bushing on the frame, a rack wheel journaled on the frame intermediate said stake and toothed bar, and means adapting said rack wheel for selective 130 use with said stake and bar.

2. The combination in a portable sawing machine with a main frame and a removable anchoring stake carried thereby, of a supporting wheel having a stationary guide member for co-action with the frame, and means carried by the frame for selective use with said guide member for adjusting the
- 5

frame and with said stake for removal of the latter.

In testimony whereof we affix our signatures.
